UNITED STATES PATENT OFFICE.

CHARLES A. FOWLER, OF SALT LAKE CITY, UTAH.

AUXILIARY LOCK FOR SAFE AND VAULT DOORS.

Application filed February 10, 1925. Serial No. 8,101.

This invention relates to an improvement in auxiliary locks designed especially for use and to be operated in combination with the locking mechanism of vault and safe doors.

One object of this invention is to provide an auxiliary lock which by reason of the adjustability and various lengths of the connecting rods the auxiliary lock can be placed 10 to operate vertically or horizontally in parallel relation to a cross bolt on a vault door regardless of the location of the permutation lock and cross bolts commonly used on the vault door.

Another object of this invention is to provide an auxiliary lock connected by a rod to an operating lever operated by a permutation lock mechanism adapted to cause directly the operation of the auxiliary lock 20 in combination with the movement of the tumblers and bolt of the permutation lock in the movement of locking and unlocking the door.

Another object of this invention is to provide an auxiliary lock to work in combination with the spaced bolts on a vault door and to lock said bolts with the locking of the vault door.

Another object of this invention is to provide an auxiliary lock that will be automatically thrown in the emergency locked position when the main locking mechanism on the door is tampered with for unauthorized entrance to the vault.

Another object of this invention is to provide an auxiliary lock, whereby the moment the handle of the door is moved downward to move the cross bolts to the locked position, the tumblers of the combination will 40 be automatically thrown back and set the lock.

Another object of this invention is to provide an auxiliary lock that is always locked with the locking of the permutation lock 45 and to be further locked or thrown in an emergency locked position when the main locking mechanism is broken off the door.

With these and other objects in view my invention consists of the following arrangements of parts to be hereinafter described and claimed.

Reference being had to the drawings forming a part of this application and to the

figures of reference marked thereon, in which:

Figure 1 is a view showing the inside of a vault door with my invention applied thereon and showing it in an unlocked position.

Fig. 2, is a section on line 2—2 Fig. 1. 60

Fig. 3, is a view showing the inside of a vault door with my invention applied thereon and showing it in a natural locked position.

Fig. 3^A is a side view of the connecting 65 rod 2.

Fig. 4, is a view showing the inside of a vault door with my invention applied thereon and showing it locked in emergency position after the permutation lock has been 70 broken off by driving in the spindle.

Fig. 5, is a view of a permutation lock with the cover removed to show the locking bolt in a locked position.

Fig. 6, is an end view of the locking 75 bolt F.

Fig. 7, is a plan view of the lower emergency lock.

Fig. 8, is a side view of Fig. 7.

Fig. 9, is a fragmentary view of a vault 80 door showing dial and handle for throwing the bolts on the door in and out of a locked position.

Fig. 10, is a plan view of the upper emergency lock.

Fig. 11, is a side view of Fig. 10.

Fig. 12, is a fragmentary sectional view of the upper end of the emergency locking pawl showing the bolt and spring for locking and holding the same in the emergency 90 position.

Fig. 13, is a side view of the operating lever.

Fig. 14, is an end view of Fig. 13.

Fig. 15, is an enlarged fragmentary view 95 of the connecting rod showing the offset therein.

Similar letters and numerals refer to like parts throughout the several views of the drawings.

The reference character A denotes a vault door, B and B' the emergency locks placed thereon, C, C' and C'' the cross bolts on the door, D a flange adjacent to the edge of the door through which the cross bolts 105 project and operate, E denotes the casing

of a permutation lock, F the locking bolt, G the dog, J the tumblers of the permutation lock. H the cover for the casing. P denotes the locking catch, L the handle and 5 M the dial on the door.

1 denotes the operating lever; 2 the connecting rod between the operating lever and the auxiliary lock B. 3 denotes the base plate for the upper auxiliary lock B. 4 the 10 lifting rod which connects the upper auxiliary lock B with the lower auxiliary lock B'. 5 denotes the base plate of the lower auxiliary lock B', 6 a drill proof disk which revolves between the casing E and the door 15 plate upon the spindle 7.

Having described the parts of my invention I will explain the construction and applying the same to a vault door.

The upper auxiliary lock B comprises a 20 base plate 3 secured to the inner face of the door by screws 11, said base plate having an arm 10 projecting upward therefrom with a hole 8 therein near the upper end thereof and a lug 9 projecting from the side 25 of said base plate and integral therewith, said lug having a hole therein in which is placed a pin 11' upon which the locking pawl 12 is pivotally carried and secured thereon by a thumb screw 13.

30 The locking pawl 12 has a projection 14 on the lower end thereof and at a right angle therefrom, said projection having a hole 14' therein in which is placed an eye bolt 15 the end thereof being riveted to 35 maintain it in said hole but not enough to prevent it turning in said hole as it must be journaled therein to turn with the raising and lowering of the locking pawl 12.

On the upper end of the locking pawl 12 40 is drilled a hole 17 in which is placed a spring 18 and a bolt 19. The bolt 19 having a notch 20 in the inner end thereof and the outer end thereof having a tang 21 thereon. On the upper end and at the side 45 of the locking pawl 12 is secured a yoke 16 for supporting the end of a screw 16' which passes through a hole crosswise of the end thereof and is secured by a thread in a hole in said yoke, said screw to hold the spring 50 within the opening 17 and to support the upper end of the connecting rod 2. The bolt 19 is held within the opening 17 by the arm 10.

Over the lug 9 is placed a spring 40'' the 55 inner end thereof being bent and placed within a hole 23 in the base plate 3 the other end thereof being bent at a right angle and placed under the upper end of the locking pawl 12.

60 The lower auxiliary lock B' comprises a base plate 5 secured to the inner face of the door by screws 26, said base plate having a lug 27 projecting therefrom and integral therewith, said lug having a pin 29 secured therein upon which is pivotally se-

cured a locking catch 28. A spring 33 is placed over said lug the inner end thereof being placed in a hole 33' in the base plate and the other end thereof being bent at a right angle and placed in a hole 31 of the locking catch 28, thus completing the construction of the emergency locks.

65 The emergency lock B can be used in place of the emergency lock B' if so desired, thus giving two locks having the emergency 70 tang therein applied to the door.

The casing E of the permutation lock has a bottom 35 thereon and integral therewith, one end thereof projecting by the end of said casing having a hole 34 therein and a lug 36 on the under side thereof. On the opposite end from said projection and at the corners thereof are other lugs 37 with holes therein, said holes to receive screws for securing said casing to the inner face of 85 a vault door, said lugs for holding said casing away from said door so a drill proof disk 6 can be placed over the spindle 7 and between the casing E and the door.

90 The cover of the casing has a slot 38 95 therein through which passes a pin 39 on the locking bolt F to engage a slot 39' in the operating lever 1.

95 The operating lever 1 is shaped like a bell crank lever having a slot 39' in the short arm and a hole 40' at the fulcrum bend thereof. The opposite end is bent sidewise at a right angle 41 and outward at 42 having a hole 100 therein to receive the lower end of the connecting rod 2. The hole 40' in the lever 1 is placed over the end of a screw 40 which holds the cover on the casing, a thumb nut 90 is now placed on the screw 40 to pivotally secure the bell crank lever to the casing.

105 The connecting rod 2 comprising an upper section and a lower section secured together by blocks 44 which are riveted thereto and form the required offset to allow the connecting rod to pass between the cross bolts C and C' and the door. The upper end of said connecting rod being pivotally secured to the pawl 12 and the lower end thereof being pivotally secured to the operating lever 1.

110 In the drawings I show one of the standard makes of a permutation lock. To make this lock to comply to my invention I take the bolt F out and place therein my bolt F which has a piece of metal 48 secured thereon to which a pin 39 is secured. The end of said bolt having a notch 50 therein to receive the end of the dog P on the door.

115 The lifting lever 4 comprises two sections. On the upper end of the upper section a thread is cut thereon, a pin placed through said section below said thread and a spring 125 51 placed thereon and said end is then placed through the eye bolt 15 on the locking bolt 12 and secured therein by nuts 51'.

120 The upper section and the lower section of the rod 4 are connected by a fusible link 130

52, the lower end thereof connecting with a link 53 which in turn is connected to the lower auxiliary lock B'.

5 The connecting rods 2 and 4 are made in many shapes and lengths so they can be secured at any place on the door regardless of the location of the permutation lock or bolts on the door.

10 In applying the invention to a vault door the permutation lock that is on the door is removed and a drill proof disk 6 having a hole in the center thereof is placed over the spindle 7 the casing E then placed thereon and secured thereto with screws through 15 the holes in the bottom thereof. The bolt F is then removed and my bolt F placed therein. After the permutation lock mechanism has been all replaced within the casing the cover H is secured thereon. The 20 operating lever is then pivotally secured to the cover H. The upper edge of the casing E has a staff 54 secured thereto over which is placed a ring 55 to which one end of a chain 56 is secured while the other end of 25 said chain is secured to a screw 57 secured in the door face. On the upper end of said staff is secured one end of a spring 58 and the other end thereof being secured within a hole 59 to the operating lever 1.

30 Now secure the auxiliary locking bolts B and B' to the face of the door at the location desired above cross bolts C' and C'' having the cross bolts in the locked position so they can be marked at the point of contact with the lower end of the locking pawls 12 and 28. At this point a notch 65 and 66 must be cut in the bolts so the ends of the pawls 12 and 18 will fit therein. The cross bolts must be removed from the door for the 35 cutting of the notches. At the vertical end of the notch 65 in the cross bolt C' is secured a block 60 to reinforce the notch. Before the block 60 is secured to the cross bolt C' the bolt must be placed back on the door 40 to its former position and then the block secured thereon.

45 After the cross bolts B' and C'' have been placed back on the door, the connecting rod 2 is placed back of cross bolts C and C' the upper end thereof being secured to the pawl 12 by a screw 16' and the lower end to the operating lever 1 and securing rod 4 as described the invention is ready for operation.

50 A roller 62 is secured to the door face below the disk 6 to prevent said disk from dropping to the floor of the vault after the spindle has been driven in or pulled out.

55 In the operation of my invention; the movement of bolt F and auxiliary locks B and B' is accomplished by the direct action of a series of rotary tumblers J of a permutation lock. A dog G pivoted at one end to a bolt F carrying at the other end a projection 63, when the tumblers are arranged

in a certain position it falls into a notch or gate 64 and then when the tumblers are moved they will throw the bolt F and the auxiliary locks in an unlocked position as shown in Fig. 1.

70

In locking a vault door handle L is moved downward raising latch P upward and in alinement with notch 50 releasing bolt F, then spring 58 in coaction with springs 33 and 40' moves operating lever upward, 75 moves bolt F outward placing notch 50 over catch P, raising projection 63 out of notch 64 allowing it to ride on the periphery of the tumblers J, turning tumblers at the same time by means of the dog G, slightly raising the upper end of locking pawl 12 by connecting rod 2, placing lower end of pawl 12 in notch 65, at the same time lowering locking pawl 28 through the connecting rod 4 into the notch 66, by this movement all bolts 80 become locked at the same time.

80

85 Whenever the handle L is moved downward the locks will be placed as shown in Fig. 3. To keep the bolts in an unlocked position handle L must be placed outward 90 as shown in Fig. 1.

90

In the above movement the vault door can be kept locked during the day time. As the combination tumblers are only moved slightly and all that is to be done is to move 95 dial M to the unlocking point and the door can be opened.

95

With my invention on a vault door it is almost impossible for the door to be closed on any one in the vault. Or to lock any 100 one in the vault in case of robbery. If one should be forced into the vault by a burglar he would find the handle was locked and he could not close the door with the handle in the downward position.

100

105 In event a robbery was being committed the vault door being unlocked any one who was able to reach the door could close it. Or in the event people were being driven into the vault by a burglar and the cross 110 bolts were not in their locked position they could push the handle down and the bolts would become locked so that door could not be closed.

110

115 In the event that the vault door was tampered with to secure entrance thereto by other means than working the combination, such as burning, driving in or pulling out the spindle, drilling through door plate to pick the combination lock or to fill with 120 powder to blow the door to remove the permutation lock, the action on the auxiliary locks will be as follows.

120

125 In burning through the door the heat would soon melt the fusible link 53 on rod 4 thus allowing the rod to drop down out of arms reach of a burglar. In the event that a burglar was burning out the permutation lock the flame as soon as it came in contact with the rod 2 would melt it thus releasing 130

pawl 12 into the emergency position as shown in Fig. 4.

If the spindle should be driven in, cover H would be broken off from casing E, rod 2 would be broken as shown in Fig. 4 the auxiliary locks would then drop into their emergency locked position.

In case the spindle was drawn out, disk 6 would drop downward to the roller 62 thus covering the hole in the casing through which the spindle went, thus preventing a burglar from picking the lock.

If a burglar drilled through the face of the door so he could pick the lock his drill 15 would strike the drill proof disk 6. As the disk revolves on spindle 7 the drill would not be able to get a hold on the disk. And in the event a burglar desired to fill this hole with powder and blow the permutation

20 lock off the door the result would be casing E would be forced off the door by the explosion, chain 56 connected to staff 54 and secured to the vault door would prevent the casing pulling the auxiliary locks in their 25 unlocked position, but will give them time to be locked into emergency providing rod 2 was not broken.

In the event that a burglar drilled a hole 30 through door plate at bolt end of permutation lock intending to saw bolt F or catch P in two so the cross bolts C, C' and C'' could be thrown in an unlocked position, he would find after doing this that the door still remained locked.

35 To open vault door after auxiliary lock B has been thrown into emergency locked position.

When auxiliary lock B and B' are placed 40 on a vault door, a measurement of their location is taken and placed away for record. In opening the door this record must be used to give the exact location of the auxiliary locks. At the location of the upper auxiliary lock a hole is made through the 45 door to allow the necessary tools to be placed therethrough to remove the tang 21 out of the hole 8 in arm 10 after so doing the upper end of pawl 12 is moved downward to the position shown in Fig. 1 to raise the 50 lower end out of notch 65. If connecting rod 4 is not broken the lower auxiliary lock will be raised out of notch 66 at the same time that pawl 12 is removed from notch 65. If rod 4 is broken a hole will have to be drilled 55 through door face and a tool placed therethrough to lift pawl 28 out of notch 66 before the door can be opened. After this is done the cross bolts on the door can be moved and the door opened.

60 After vault door has been opened and all broken parts replaced by new parts all auxiliary locks can be left in the same place or changed to some other location on the door.

65 While the operation of this invention is very similar to my application Filed April

18, 1924 Serial No. 707,474, there are many improved features thereof, which, I claim, and desire to secure by Letters Patent, is:

1. An auxiliary lock in combination with a vault door a locking device on the door 70 including a bolt mechanism and a permutation lock mechanism, said permutation lock mechanism having a casing therefor with a removable cover thereon, an operating lever pivotally mounted on said cover, a bolt with- 75 in said casing projecting therefrom having a pin thereon passing through a slot in said cover and engaging a slot in said operating lever to operate said lever when said bolt is operated by said permutation lock mecha- 80 nism, said bolt having a notch in the outer end thereof to engage a catch of said locking device on the door, substantially as de- scribed.

2. An auxiliary lock in combination with 85 a vault door having a flange adjacent to the edge thereof, a locking device for the door including a plurality of spaced bolts arranged to project through said flange and a bar connecting said bolts, an auxiliary lock 90 comprising a base plate carried by the door face, a locking pawl carried by said base plate, a rod pivotally connected to said auxiliary lock and extending in relation to the door face, a lever pivotally secured to the 95 casing of said combination mechanism, the other end of said rod connected to said lever and means for operating said auxiliary lock and lever in coaction with the combination mechanism substantially as described. 100

3. An auxiliary lock in combination with a vault door having a flange adjacent to the edge thereof, a locking device on the door including a combination mechanism, a plurality of cross bolts arranged to project 105 through said flange and a bar connecting said bolts, an operating lever pivotally secured to the casing of said combination mechanism, said auxiliary lock consisting of a base plate carried on the door plate and a locking pawl pivotally secured thereto, a rod one end thereof pivotally secured to said pawl and the other end thereof pivotally secured to said operating lever, another rod pivotally connecting said pawl with another 110 auxiliary lock secured to said door plate, said rods for operating said auxiliary locks 115 when said operating lever is operated by said combination mechanism.

4. An auxiliary lock in combination with 120 a vault door a locking device for the door including a bolt mechanism and a combination mechanism, a base plate mounted on the face of said door, a locking pawl pivot- 125 ally mounted on said supporting member, another base plate carried by said door face, another locking pawl pivotally mounted on said other base plate, said locking pawls to engage notches in said bolt mechanism, means for connecting said locking pawls together 130

and means operated by said combination mechanism for operating said locking pawls in coaction with said combination mechanism.

5. An auxiliary lock in combination with a vault door a locking device on the door including a bolt mechanism and a combination mechanism, said auxiliary lock comprising a base plate having an arm secured on the door face, a locking pawl fulcrumed on said base plate and adapted to engage a slot in a cross bolt on said door, an operating lever for keeping said locking pawl in a co-active movement with the combination mechanism on the door, a spring for throwing said locking pawl into an emergency locked position, said locking pawl having a hole in the upper end thereof, a spring and bolt placed within said hole, said spring to move said bolt into a hole in the arm of said base plate when said locking pawl is thrown into an emergency locking position substantially as described.

6. The combination with a vault door having a flange extending adjacent to the edge thereof, a locking device on the door including a plurality of bolts arranged to project through said flange and a bar connecting said bolts, a base plate secured to the door plate, a pawl pivotally mounted on said base plate and adapted to engage a slot on a cross bolt of said door, a locking pin in the upper end of said pawl operated by a spring within said pawl for holding said pawl in an emergency locked position and means in said base plate to engage said pin when said pawl is in emergency locked position.

7. An auxiliary locking device in combination with a vault door, a locking device for the door including a combination mechanism and a bolt mechanism, said combination mechanism having a casing therefor with a sliding bolt therein, said bolt having a pin projecting therefrom and passing through a slot in said casing and engaging a slot in an operating lever pivotally connected to said casing, said sliding bolt and pin for operating said lever in the movement of the combination mechanism, a drill proof washer carried by the spindle for said combination mechanism and placed between said casing and door plate, a roller mounted on a bolt secured to the door plate below said washer upon which said washer rests when said spindle has been driven in or pulled out substantially as described.

8. In combination with a vault door a locking device on the door including a bolt mechanism and a combination mechanism, an auxiliary locking device for the door consisting of a base plate mounted on the door plate, a locking pawl pivotally carried by said base plate and adapted to engage a cross bolt of said bolt mechanism, means for moving said locking pawl into a

locked position by the movement of the combination mechanism, means for placing said locking pawl in an emergency locked position and means for holding said pawl in emergency locked position upon the breaking of the combination mechanism substantially as described.

9. The combination with a vault door having a plate with a flange adjacent to the edge thereof a locking device on the door including a bolt mechanism arranged to project through said flange and a bar connecting said bolt, a base plate secured to said plate, a locking pawl pivotally secured to said base plate, said locking pawl having an opening in the upper end thereof, a spring and bolt placed within said opening, said spring to move said bolt in the emergency locking position when said locking pawl is forced down by another spring into a notch in a cross bolt of said locking mechanism when the combination mechanism has been broken off the door.

10. An auxiliary locking device in combination with a vault door having a flange extending adjacent to the edge thereof a locking device on the door including a combination mechanism, and a bolt mechanism arranged to project through said flange and a bar connecting said bolt mechanism, a lever rotating upon a pin secured to the casing of said combination mechanism, said casing having a sliding bolt therein, a pin attached to the side of said sliding bolt passing through a slot in said cover arranged to engage a slot in said lever, said pin for operating said lever in the movement of said bolt by the combination mechanism, said casing having a staff thereon over which is placed a ring having one end of a chain secured thereto, the other end of said chain being secured to a bolt in the door face, said chain to prevent said casing falling to the floor when broken off the door, the end of said staff having one end of a spring attached thereto the other end of said spring being attached to said lever, said spring for operating said lever when a handle on the door is downward, a locking pawl having a base plate secured to said door in parallel relation to a bolt of said bolt mechanism, said locking pawl having one end of a rod pivotally connected thereto and the other end of said rod being pivotally connected to said lever, another rod pivotally connected to said locking pawl and to another locking pawl having a base plate secured to said door in parallel relation to another cross bolt of said bolt mechanism, said lever and rods for operating said auxiliary locks in the movement of said combination mechanism and means for locking said auxiliary locks into an emergency position.

11. An auxiliary locking device in com-

- bination with a vault door having a flange adjacent to the edge thereof, a locking device on the door including a combination mechanism a plurality of cross bolts arranged to be projected through said flange and a bar connecting said bolts, said auxiliary locking device consisting of a lever pivotally mounted on the casing of said combination mechanism, an operative bolt within said casing operated by said combination mechanism, a pin projecting through a slot in the cover of said casing adapted to engage a slot in said lever, a base plate carried on the door, a locking pawl pivotally secured to said base plate, means for supporting said locking pawl on said base plate, a rod connecting said locking pawl with said lever, another base plate secured to the door having another locking pawl supported thereon, a rod pivotally connecting said locking pawls, another rod pivotally connecting one of said locking pawls with said operating lever, said rods and lever for operating said auxiliary locks when said combination mechanism is moved, said locking pawls placed on said door in parallel relation to the cross bolts on said door and adapted to be engaged with a notch on said cross bolts, substantially as described.
12. An auxiliary lock in combination with a vault door having a flange adjacent to the edge thereof a locking device on the door including a combination mechanism and a bolt mechanism arranged to be projected through said flange, said auxiliary lock consisting of a base plate secured to the inside of said door in parallel relation to a cross bolt of said bolt mechanism, a pawl pivotally secured to said base plate, said base plate having a spring mounted thereon for operating said pawl, said pawl having a hole in the upper end thereof in which is placed a spring and a bolt, said base plate having an arm projecting therefrom upon which slides the end of said bolt when said pawl is operated, means on said arm for receiving the end of said bolt when said pawl is in an emergency locking position, the lower end of said pawl to fit within a notch in a cross bolt of said door, and means for operating said pawl in the moving of said combination mechanism.
13. The combination with a vault door having a bolt locking mechanism and a combination locking device, an auxiliary locking device comprising a base plate secured to the inner face of the door, said base plate having an arm projecting therefrom with a hole therein near the upper edge thereof, a locking pawl, said base plate having a lug projecting from the face thereof with a pin therein upon which is fulcrumed said locking pawl, said locking pawl having an eye bolt pivotally secured in the lower end thereof, an emergency locking bolt, the upper end of said locking pawl having a hole therein in which is placed a spring and said emergency locking bolt, said spring for operating said bolt, a connecting rod, said spring being secured in said hole by a screw one end of said screw pivotally connecting with the upper end of said connecting rod, means pivotally connected to the other end of said connecting rod for operating said auxiliary lock in coaction with the combination mechanism, another connecting rod having a fusible link thereon and another link on the lower end thereof, said other connecting rod for connecting said locking pawl with another locking pawl secured to the door face by a base plate, said locking pawls being secured to the door face in parallel relation to the cross bolts of the door substantially as described.
14. In combination with a vault door having a flange extending adjacent to the edge thereof, a locking device for the door including a plurality of spaced bolts arranged to project through the flange, and a bar connecting said bolts a combination mechanism and a casing for said combination mechanism, one end of said casing having a projection thereon with a lug thereunder and the other end of said casing at the corners thereof has lugs thereunder, said lugs having holes therein for securing said casing to the door, a cover for said casing having a slot therein through which passes a pin on the combination locking bolt, a drill proof disk placed between said casing and said door, said disk being supported by a spindle on the door of the combination mechanism, a roller secured to said door below said disk upon which said disk will drop when said spindle has been driven in or pulled out substantially as described.

In witness whereof, I affix my signature,
CHARLES A. FOWLER.
